[57] CLAIM

The ornamental design for a plant stem holder, as shown and described.

DESCRIPTION

FIG. 1 is a perspective view of a plant stem holder showing my new design;

FIG. 2 is an enlarged perspective view of the base portion thereof;

FIG. 3 is an enlarged side elevational view of the base portion thereof, the adjacent sides being substantially similar in appearance;

FIG. 4 is an enlarged top plan view of the base portion thereof;

FIG. 5 is an enlarged bottom plan view of the base portion thereof;

FIG. 6 is an enlarged perspective view of the tree-rod portion thereof; and

FIG. 7 is an enlarged perspective view of one of the arms of the tree-rod portion thereof.

The tree-rod portion has been omitted from FIGS. 1-5 and the base portion omitted from the remaining figures for clarity of illustration.
